UNITED STATES PATENT OFFICE.

FREDOLF PETERSON, OF SALEM, OHIO, ASSIGNOR TO THE AMERICAN CASE & REGISTER COMPANY, OF SALEM, OHIO, A CORPORATION OF OHIO.

LEAF FOR CREDIT-REGISTERS.

1,007,384.

Specification of Letters Patent. Patented Oct. 31, 1911.

Application filed May 19, 1911. Serial No. 628,346.

To all whom it may concern:

Be it known that I, FREDOLF PETERSON, a subject of the King of Sweden, residing at Salem, in the county of Columbiana 5 and State of Ohio, have invented certain new and useful Improvements in Leaves for Credit-Registers; and I do hereby declare the following to be a full, clear, and exact description of the invention, reference being 10 had to the accompanying drawings, and to the letters and figures of reference marked thereon, which form a part of this specification.

This invention relates to leaves for credit 15 registers and filing appliances used by merchants in credit accounting or filing systems. The invention having relation to the construction of the leaves going to make up the filing device or credit register.

20 In the accompanying drawing—Figure 1 is a perspective view of a credit account leaf. Fig. 2 is a perspective view showing a portion of one of the leaves of the system, the leaf being shown in longitudinal section. Fig. 3 is a section of the leaf showing the hinge clip placed in proper position. Fig. 4 is a detached view of one of the strips. Fig. 5 is a perspective view showing a portion 25 of a leaf and illustrating one of the strips in proper relative position showing the strip in longitudinal section. Fig. 6 is a view showing a portion of the leaf in its unfolded condition.

Similar numerals of reference indicate 30 corresponding parts in all the figures of the drawing.

In the accompanying drawing, 1 represents the sheet or leaf which is formed of a size such as are commonly used in credit 35 account appliances. The bottoms of the sheet 1 or more specifically the leaves are provided with the integral folded portions 2, 3 and 4, which folded portions constitute a base, which base is formed of sufficient 45 width to provide room between leaves for the bars or strips 5. For the purpose of giving the desired amount of rigidity to the bases of the leaves the bars 6 are provided around which bars are folded the parts 2, 3 50 and 4 of the leaves 1. The strips 5 are preferably formed of metal and are hollow, and their upper and lower ends provided with the tangs 7. That portion of the metal which is folded to constitute the bases of

the leaves is provided with the cut out portions or apertures 8, which apertures are so located that they will come in practical alignment with the line of folds or bends indicated by the dotted lines 9, Fig. 6, which are the points of folding around and upon 60 the longitudinal edges of the bars 6, so that when the metal has been folded as illustrated in Figs. 2 and 5, the cut out portions or apertures will be located at the longitudinal edges of the bases and in position to receive the tangs 7 formed upon the bars or strips 5, this feature being illustrated in Figs. 2 and 5.

For the purpose of providing means for 65 hinging a series of leaves together, the bases are provided with the clips 10, which clips are provided with the hinge eyes 11, said hinge eyes being arranged in the usual manner.

The construction of the leaves is substantially 70 the same regardless of the number of leaves employed and the present invention has no specific reference to credit cabinets save and except the particular construction 75 of the leaves.

For the purpose of assisting in securely 80 holding the strips 5, rivets or their equivalents are employed. The tangs 7 perform the double function of closing the hollow strips 5 at their upper ends and at the same 85 time assist in holding the extreme lower ends of the strips in proper relationship with reference to the leaves and the lateral flanges constituting the base of the leaf.

Having fully described my invention what 90 I claim as new and desire to secure by Letters Patent, is—

1. In a leaf for credit registers, the combination of a leaf provided with lateral folded portions, apertures formed in the 95 material of the leaf at the folds, strips secured to the faces of the leaf, said strips provided with tangs, said tangs adapted to be seated in the apertures located at the folds, substantially as and for the purpose 100 specified.

2. In a leaf for credit registers, the combination of a leaf provided with lateral folded portions, a bar located within the 105 folded portions, apertures formed in the material of the leaf at the folds, strips secured to the faces of the leaf, said strips provided with tangs, said tangs adapted to

be seated in the apertures located at the folds, substantially as and for the purpose specified.

3. In a leaf for credit registers, the combination of a leaf provided with lateral flanges, recesses located in the flanges, strips provided with tangs, said tangs adapted to be seated in the recesses formed in the flanges and hinge clips secured to the

flanges, substantially as and for the purpose 1 specified.

In testimony that I claim the above, I have hereunto subscribed my name in the presence of two witnesses.

FREDOLF PETERSON.
